UNITED STATES PATENT OFFICE.

WILLIAM E. BELKE, OF CHICAGO, ILLINOIS.

PLATING TANK.

Application filed April 14, 1927. Serial No. 183,731.

This invention relates to electroplating tanks in which power-driven means are provided for handling the articles to be plated.

The main objects of this invention are to provide an improved form of plating tank in which the articles to be plated can be handled with a minimum amount of manual labor; to provide a plating tank having power-driven mechanism for immersing and raising the articles which are being plated; and to provide a container for the articles being plated which can be moved so as to agitate the articles therein for securing uniform plating.

An illustrative embodiment of this invention is shown in the accompanying drawings, in which:—

Fig. 1 is a perspective view of the electroplating machine, a portion of the tank being broken away to show the interior thereof.

Fig. 2 is a perspective view of the same from the opposite side, showing the operating mechanism for the container which holds the articles being plated.

Fig. 3 is an enlarged perspective view of the container for the articles to be plated.

Fig. 4 is an enlarged perspective view of an arbor which is adapted to be supported in the center of the container and which carries a plurality of depending, loosely mounted fingers for making electrical contact with the articles placed in the container.

Fig. 5 is an enlarged, fragmentary, sectional detail of one end of the container and supporting means therefor, showing one of the removable pintles, and the means of making electrical connection therethrough.

Fig. 6 is a plan view of the removable panel of the plating drum.

In the construction shown in the drawings, the apparatus comprises a tank of suitable material, such as wood, securely bolted together and made water-tight, for containing an electroplating solution, or electrolytic bath in the usual manner, and a drum or cylindrical container adapted to receive and retain the articles while they are being electroplated, and which is actuated by two series of operating mechanisms, one series of which is for the purpose of lowering and raising the drum into and out of the electroplating bath, and the other series of which is arranged to rotate the drum while immersed in the solution.

The tank 1 is preferably formed of a plu-

rality of boards or planks securely bolted together by tie-rods and bolts 2 in the usual manner in which electroplating tanks are constructed. Resting on the top of the tank, at opposite sides thereof, and closely adjacent to the ends of the tank, are supporting rods 3 and 4 which carry a plurality of anodes 5, suspended therefrom and extending down into the tank closely adjacent to the bottom thereof, the lower ends of which are curved inwardly towards each other, as shown at 6. Suitable lead wires 7 and 8 are provided for the rods 3 and 4 respectively for conducting the current to the anodes in the usual manner.

A receptacle is provided for receiving and holding the articles which are to be electroplated, and comprises a drum 10, having end plates 11 and 12, preferably formed of wood and bound around their outer peripheries with iron straps 13 and 14 suitably secured thereto by screws 15. The ends 11 and 12 of the drum are held in spaced relation by a series of transverse bars 16, which are placed in equally spaced relationship about the peripheries of the end pieces, and which are suitably grooved to provide seats for a plurality of elongated panels 17 which are retained therein by molding strips 18, fastened to the cross bars by screws 19. The panels are all provided with a plurality of closely positioned perforations 20, so as to allow the admission of fluid to the interior of the drum and at the same time retain the articles to be plated therein. One of the panels 25 is arranged to be readily removable, and is provided with a suitable fastener 26 secured to one end thereof, which coacts with a fastener 27, that is fastened in a notch 28 formed in the periphery of the end piece 12. The notch 28 is deep enough to receive the fasteners 26 and 27 without the fasteners protruding beyond the normal peripheral surface of the drum. The end piece 11 is provided with a removable pinte pin 30 concentrically located with respect to the head, and protruding a short distance from the inner side thereof. The pin 30 is carried in the hub portion of a flange 31 which is secured to the outer surface of the end piece 11, and retained therein by a screw 31^a. The flange is provided with an outwardly protruding hub, upon which is keyed or otherwise suitably secured a sprocket wheel 32, in spaced relation to the flange 31. Said space between

the flange 31 and sprocket 32 provides a bearing surface for a drum supporting arm 39^a at that side thereof.

The end piece 12, at the opposite end of the drum, is provided with a concentrically located pintle 35, mounted concentrically in a tubular sleeve 46 of suitable insulating material, such as hard rubber, which is carried in an outwardly extending hub 38 of a flange 36. The flange 36 is secured to the end piece 12 by suitable means, such as screws 37. The hub 38 also provides a bearing surface for a drum supporting arm 39 at that side thereof, which is retained thereon by a collar 40 that is held in place on the hub 38 by a set screw 41. The outer end of the axial bore through the sleeve 46 is closed by a screw 45, preferably of hard rubber, which is threaded into the bore.

20 The end of the pintle pin 35, adjacent the screw 45, is drilled and threaded to receive the threaded end 35^a of a copper rod 35^b, which is surrounded by an insulated sleeve or tube 47. The tube 47 and rod 35^b are supported and carried by the tubular head 48, rigidly mounted on the arm 39. A suitable electric lead wire for the electroplating circuit is attached to the copper rod 35^b at its outer end.

25 This construction provides a heavily insulated electrical conductor for the electroplating circuit through the rod 35^b and pin 35 into which the rod is threaded.

In order that the electrical contact will be maintained at all times with the articles placed in the drum 10 to be electroplated, an arbor or supporting bar 50 is provided which has weighted yokes 51 and 52 mounted on the opposite ends thereof, and secured thereto by set screws 53 and 54 respectively. The yokes are identical in construction, and have a pair of spaced parallel arms 55 and 56, which terminate in enlarged portions 57 and 58, said enlarged portions being of 45 a weight sufficient to keep them from rotating when placed on the pintles 30 and 35 and the drum rotated. The supporting bar 50 is provided with a series of depending fingers 60 loosely mounted thereon and held 50 in spaced relation to each other by spacing sleeves 61, said fingers being of a length substantially the same as the radius of the drum so that the ends of the fingers terminate in closely spaced relation to the perforated 55 panels, but out of contact therewith.

The back edge of the tank has a pair of upwardly and forwardly curved projecting supporting arms 65 bolted thereto, and the upper ends of the arms terminate in transversely bored trunnion heads 66 for receiving a main supporting shaft 67. The drum supporting arms 39 and 39^a are keyed to the shaft 67 in spaced relation so as to receive the drum 10 therebetween. Midway 60 between the point of support of the drum

supporting arms is keyed an upwardly projecting arm 70, the upper end of which terminates in an elongated transversely disposed head 71, which is suitably bored and threaded to receive a shaft 72, upon which 70 is adjustably mounted a counterweight 73 which can be secured at any position thereon by a set screw 74.

Means are provided for rotating the main shaft 67, and thereby swing the arms and 75 drum supported thereon into and out of the electrolytic bath, and comprise an electric motor 75 which drives a worm 76 which engages a gear 77. The gear 77 in turn drives a worm 78, which coacts with a gear 79 which is rigidly keyed to the main shaft 67. This motor is of the reversible type, and is wired to a double-throw switch 80, preferably mounted at the front of the tank in convenient position to be operated by the 80 user of the tank.

In place of the reversible motor, a suitable reversing gear can of course be substituted and used for accomplishing the same 90 purpose.

When articles have been placed in the drum and the drum immersed in the electroplating bath, it is desirable that the drum be so moved or rotated that the articles 95 therein will be agitated so as to receive a uniform plating thereon. Means are provided for rotating the drum in this manner, and comprise an electric motor 85, mounted on the bracket 86, bolted to one side of the tank. The shaft of the motor carries a worm housed in an oil container 87, which drives a gear 88 keyed to a sleeve 89, and is mounted on the main shaft 67. The inner end of sleeve 89 has a sprocket gear 90 keyed thereto, which carries a sprocket 100 chain 91, that is in alinement with the sprocket gear 32 of the drum 10. A suitable switch 93 is preferably mounted on the front side of the tank for controlling the 105 motor 85.

In the operation of the device, the drum is rotated until the removable panel is uppermost, and then the panel removed, and the articles to be electroplated are placed in the container. The supporting bar which carries the contact fingers 60 is then placed in position on the pintles 30 and 35, the fingers 60 coming in contact with the articles to be electroplated. The panel is then replaced and locked in position by the fasteners 26 and 27, and the switch 80 operated so as to cause the electric motor 75, through its reduction gear, to rotate the shaft 67 and thus swing the drum 10 downwardly into the electroplating bath, and to a position 115 which will be substantially equally spaced from the anodes 5. The lower ends of the anodes being curved in at 6, causes them to assume a concentric position with respect to the drum when the drum is properly posi- 120

125

130

tioned in the tank. The switch 93 is then closed, thus causing the motor 85, through its reduction gearing and sprockets and sprocket chain, to rotate the drum in the bath. During this rotation the weights 57 and 58 on the supporting bar 50 prevent the bar from rotating and thus keep the contact fingers 60 in electrical contact with the articles being electroplated. The current for the plating operation is turned on at the same time that the container is lowered in the bath, the electrical contact being made through the copper rod 35^b, which is threaded into one end of the pintle pin 35, yoke 52, bar 50, and contact fingers 60, to the articles which are to be electroplated.

The pintles 35 and 30 will become electroplated at the same time that the articles in the container become electroplated, and these pintles are made readily removable so that they can be replaced by new ones by removing the screws 45 and 31^a and reaching in through the opening when the removable panel is not in place, and lightly tapping on the inner ends of the pintles. The copper rod 35^b is of course unscrewed from the pin 35 before it is attempted to slip this pin out of its insulated sleeve. This is especially desirable, as otherwise, in a short time, with certain kinds of plating, the pintle 35 would not give a good electrical contact with the yokes 52 and supporting bar 50.

Although but one specific embodiment of

this invention has been herein shown and described, it will be understood that numerous details of the construction shown may be altered or omitted without departing from the spirit of this invention, as defined by the following claims:

I claim:

1. In an electroplating device, a tank for an electrolytic solution, an anode for contacting the solution, a pair of supporting arms each having a transverse shaft journaled thereto, a container for the pieces to be electroplated rotatably mounted on said shafts, an arbor having depending slotted ends adapted to be detachably supported by said shafts, a plurality of contact fingers depending from the arbor, means for immersing the container in the solution, and means for rotating the container.

2. In an electroplating device, a tank for an electrolytic solution, a drum for articles to be electroplated rotatably mounted in said tank, a pintle protruding inwardly from each end of said drum, an arbor for said drum, a yoke on each end of said arbor for slidably receiving said pintles, the ends of the arms of said yokes being weighted sufficiently to prevent rotation of said arbor when said drum is rotated.

Signed at Chicago this 18 day of March, 1927.

WILLIAM E. BELKE.
